UNITED STATES PATENT OFFICE.

HENRY HOTTINGER, OF CINCINNATI, OHIO.

BOOT OR SHOE.

SPECIFICATION forming part of Letters Patent No. 551,281, dated December 10, 1895.

Application filed March 7, 1895. Serial No. 540,853. (No model.)

To all whom it may concern:

Be it known that I, HENRY HOTTINGER, a citizen of the United States, and a resident of the city of Cincinnati, in the county of Hamilton and State of Ohio, have invented certain new and useful Improvements in Boots or High-Ankle Shoes, of which the following is a specification.

My invention gives all the advantages of the styles of boots heretofore made and obviates all of their disadvantages.

It also confers additional advantages not found before in any of the boots or shoes made.

15 One prominent feature of my invention consists of a novel construction, so that the boot is provided with a side lace, beginning forward or at the front end of the instep where the latter merges into the front portion 20 of the foot, and extending in a direction nearly horizontal to the ankle and then rising and extending up the side of the boot. This lacing is at the outer side of the boot rather than on the inside. The location of the lacing at the outside of the leg prevents its striking, rubbing, or in anywise abrading the surface of the companion shoe, or impeding the progress of the wearer thereof.

25 A very great convenience in locating the lacing on the side of the foot and on the outer side is that it can be readily reached—much more easily reached than where the lacing is at the front of the instep and leg. In the case of fat or fleshy individuals, or of men clad 30 in many clothes or stiff apparel, they cannot lean directly forward far enough to reach and manipulate the lacing of the shoe, nor lift the foot whose shoe is to be laced upon the knee of the opposite leg, and they are 35 thus prevented from readily accomplishing the lacing of a boot or shoe; but any one can throw their foot and leg out sidewise and leaning over to that side reach the outside of that adjacent leg and foot, and as I have there 40 located said lacing, they can reach the same with ease, and quickly and successfully lace the same. This facility constitutes in itself a marked desideratum—a valuable advantage. This advantage applies equally well where 45 the article is a boot or has the leg thereof so shortened as to become a shoe.

I am aware that a perpendicular flat lacing on the outside of a boot-leg has been heretofore used, but I have never known of a perpendicular hooked lacing on the outside of a 55 boot-leg, and I have never known of any kind of lacing flat or hooked on the outside of the instep or foot substantially as shown, and I consider these as features of my invention.

The side hooked lacing is far more easily 60 handled than flat lacing, though the latter could be used as a part of my invention and in carrying it into effect, along the side of the foot and up the leg, if the shoe fabric be thus extended.

65 By the above construction, the shoe or boot can be quickly fastened upon the wearer, and as fastened adapts itself to the shape of his foot and limb.

Another important feature of my invention 70 consists of the construction whereby the upper portion or flap at the said side lacing-opening overlaps the lower portion. The advantage of such construction is very great, as it operates to shed all rain falling upon that 75 half of the shoe, and prevents snow from entering the lacing-opening.

It is well known that hunters, surveyors, explorers, farmers, lumbermen, as well as many other classes of men who are engaged 80 in outdoor occupations are frequently compelled to go through wet bushes, grass, and the like. This wet impediment wets more than ordinary rain. By the feature of construction last mentioned, such wet is warded 85 off by the shield-flap aforementioned. The progress of the foot and leg being forward, the wet is shed off, and passed back without having opportunity to enter the lacing-opening. The advantages of such a construction 90 over the open front lace lying in the front median line of the foot and ankle are at once apparent. The latter is open to receive the wet, and as the foot is advanced catches all the moisture it comes in contact with. Thus 95 this feature of my invention is better in these particulars than the presence of a waterproof tongue, and for such purposes enables me to dispense with such a tongue in my construction where in the usual front open seam such 100 a tongue would be necessary.

Where the boot or shoe is to be used in

water deep enough to nearly or quite submerge the foot, a waterproof tongue is to be employed in connection with a shoe or boot, and this tongue is to be of a desired length.

5. The shoes or boots may likewise be provided with a cork sole above the leather sole. Having now described the principal features of my invention and many of the consequent advantages, I will now proceed to 10 describe an illustrative construction thereof.

In the drawings, Figure 1 is a view in perspective of a boot, illustrating my invention. Fig. 2 represents a vertical transverse section of said boot, taken in the plane of the dotted line 2 2 of Fig. 1. Fig. 3 is a horizontal transverse enlarged section of the leg of the boot, taken in the plane of the dotted line 3 3 of Fig. 1. Fig. 4 is a plan view of the front portion of the uppers removed from the sole and turned bottom side up, thus showing the under side thereof, illustrating the preferred construction of the linings when the boot or shoe is to be used in marshy wet ground or in water.

25. A indicates the sole, provided with the usual heel A². A cork sole A³ superincumbent on sole A may be present, as shown. The upper, generally considered, consists of two great divisions—viz., part B and part C. The part B begins at that edge of the sole nearer to the other foot—viz., M—and extends up and over the foot and down onto the opposite or outer side as far as M², as shown. The part C begins at the outer edge N of the sole and extends up as far as N². The part B thus overlaps, on the outer side of the shoe, the part C, for a considerable distance down. Such overlapping by part B of part C is carried on for the entire length of the lace-opening L, beginning at the point P forward of the instep and extending back in a nearly-horizontal line to the ankle I. Here at R the lace-opening L curves upward and then runs vertically up the ankle I. The overlapping of part B over C is likewise there continued. Where the upper and back portions are continued up the leg and form a boot-leg, the overlapping is preferably continued up the leg with the open lace, and there the overlap is from front to rear at the outer side of leg, substantially as shown in Figs. 1 and 3.

50. While the flat lace can be employed in connection with the overlap and lace-opening, I prefer to employ the hook lace as more convenient to tighten and adjust and complete in the operation of lacing the shoe or boot.

55. The preferred further detail construction of the shoe or boot is as follows: The uppers will each consist of two main divisions. The part B consists of a lower portion B² of heavy leather and a top part B³ of thinner, lighter, and more flexible leather. The part C will consist of a lower portion C² of heavy leather and an upper portion C³ of lighter, thinner, and more flexible leather. The purpose of such construction is obvious. To the inner

side of the part B³ will be attached a reinforcing-strip B⁴ for the better holding of the eyelets or preferably the hooks H, which take the place of eyelets, and preventing the same tearing out or away from their flap. The part C³ is likewise provided on the inside with a reinforcing-strip C⁴ for the better securing of the eyelets or hooks H connected to this part C³. Such reinforcing-strips will be coextensive with the lacing-seam.

60. The lower end or ends of the lacing cord or string H² is suitably secured at or near the front end of the lace-opening.

The shoe or boot may be lined with a suitable fabric or fabrics. Such lining or linings will ordinarily be present.

65. When the shoes or boots are to be used in rough and very wet walking, the parts B² and C² will each be preferably lined with a leather lining D, and the parts B³ and C³ with a lining of chamois-skin E. This lining E may extend under the reinforcements or not, as preferred. In the present illustrative instance the chamois-skin extends to the reinforcement B⁴ and under the reinforcement C⁴.

70. The usual inner back reinforcing strip or strips extend along up the rear of the shoe or boot, especially where there is a seam in the rear, as in the special style of shoe here selected for illustration.

75. When the shoe or boot is to be used in traveling where water or marshes or the like are, the usual waterproof tongue F is provided, connected at front to the upper in front of where the lace-opening begins, and sewed at each side to the respective adjacent flap or piece, as B³ and C³, substantially as shown.

80. In placing the shoe or boot on the foot and securing it there, the wearer draws on the shoe and then, throwing his foot outward, leans over sidewise and down, bringing his hand in easy reach of the lacing-seam. He then laces the shoe in the usual manner, and fastens the string H² at the top in any suitable manner. A suitable catch, as K, enables the wearer to more readily secure the upper end of the string in place.

85. In taking off the shoe the wearer assumes the same position as in lacing it up, and then unlaces it. The shoe is then removed, as usual.

90. What I claim as new and of my invention, and desire to secure by Letters Patent, is—

1. In a boot or shoe provided with a side lace opening extending from the forward part of the foot, along horizontally toward the rear, the combination of the part B having lower portion B² and its lining D, and upper portion B³ and its light lining E, and reinforcement B⁴ thereof, and the part C having lower portion C², its heavy lining D and upper portion C³ and its light lining E and its reinforcement C⁴, substantially as and for the purposes specified.

10. In a boot or shoe provided with a side

lace opening extending from the forward part of the foot, along horizontally toward the rear, the combination of the part B having lower portion B² and its lining D, and upper portion B³ and its light lining E, and reinforcement B⁴ thereof, and the part C, having lower portion C², its heavy lining D and upper portion C³ and its light lining E and its reinforcement C⁴, and the waterproof tongue within the shoe and connected to the portion B and portion C, substantially as and for the purposes specified.

HENRY HOTTINGER.
